UNITED STATES PATENT OFFICE.

WILLIAM H. TEABY, OF BERKELEY, CALIFORNIA.

GATE.

No. 831,487.

Specification of Letters Patent.

Patented Sept. 18, 1906.

Application filed June 21, 1906. Serial No. 322,713.

To all whom it may concern:

Be it known that I, WILLIAM H. TEABY, a citizen of the United States, residing at Berkeley, in the county of Alameda and State of California, have invented new and useful Improvements in Gates, of which the following is a specification.

My invention pertains to farm-gates of the kind that are adapted to be opened by a person in an approaching vehicle without the necessity of such person getting out of the vehicle; and it contemplates a simple and inexpensive farm-gate and one embodying such a construction that it is adapted to remain of itself in its open position and also in its closed position.

Other advantageous features of the invention will be fully understood from the following description and claims when the same are read in connection with the accompanying drawings, forming part of this specification, in which—

Figure 1 is a perspective view of my novel gate construction as a whole, the gate being shown in its closed position. Fig. 2 is an enlarged horizontal section taken through the gate and the gate-post in a plane slightly above the lower hinge of the gate. Fig. 3 is a top plan view of the gate, illustrating by dotted lines the arrangement of the cable relative to the lever-plate of the gate.

Similar letters designate corresponding parts in all of the views of the drawings, referring to which—

A is an upright designed to be fixed in the ground, and B is a hinge-post designed to be fixed in the ground and arranged against the face of the upright A after the manner illustrated. The said post B is provided at its upper end with an upwardly-extending stud C, having a flat horizontal arm D, and it is also provided at an intermediate point of its height with two fixed and laterally-extending wings E of U shape, and is further provided in its face at a point between the said wings E with a depression F for a purpose presently pointed out.

G is a swinging gate which in general may be of any construction compatible with the purpose of my invention. The said gate is peculiar, however, in that its inner upright bar H extends above its top bar and is provided at its upper end with a horizontally-disposed lever-plate I. This lever-plate I has a straight inner edge a and a rounded edge b, and it also has a groove c, which ex-

tends throughout the length of the edges b and c, for a purpose hereinafter set forth. On the inner upright bar H of the gate is fixed a horizontal metallic loop or staple J, which receives in its bight the stud C on the hinge-post B and serves in connection with the said stud to form the upper hinge of the gate, while on the said inner upright bar H at a point below the loop or staple J is fixed a metallic loop or staple K, which is disposed at right angles to the loop or staple J. This loop or staple K tightly holds a horizontally-disposed plate M, of metal or other material suitable to the purpose of my invention, in the rear edge of which are notches N, designed to engage the fixed wings E in the manner hereinafter pointed out in detail.

The horizontal plate M serves in connection with the wings E to form the lower hinge of the gate, and it will be apparent that when the gate is closed it will rest in a horizontal position and remain of itself in such position, because of the notches in the plate M bearing against the upright portions of the two wings E. It will also be apparent that when the gate is opened the plate M will rock on the wing E toward the direction in which the gate is swung, and consequently the gate will be moved forward or away from the hinge-post B and upward until it brings up against the face of the upright A, in which position it will obviously remain of itself until it is moved back to its closed position.

With a view of enabling persons in vehicles approaching the gate in either direction to conveniently open the gate, I provide posts P, located at opposite sides of the hinge-post B, and equipped with sheaves Q and the cable R, which is passed over the sheaves Q, and is provided at its ends with hand-grasps S. The said cable R is fastened in the groove in the inner straight edge a of the lever-plate I and is passed in opposite directions around the plate in the groove in the curved edge b, as best shown in Fig. 3.

In the practical operation of my novel gate it will be seen that a person in a vehicle approaching the gate has but to pull down on the adjacent handle S of the cable R, when the gate will be caused to swing open in a direction away from the vehicle, and this with but a minimum amount of effort on the part of the said person. When the gate is opened, as stated, it will remain of itself in such position, and then after the vehicle has passed through the gateway the gate may be closed

by swinging it to a slight extent away from the upright A, when it will gravitate to its closed position and remain of itself in such position.

5 It will be gathered from the foregoing that my novel gate is simple and inexpensive in construction and embodies no delicate parts such as are likely to be affected by the weather or to get out of order after a short 10 period of use.

I have specifically described the construction and relative arrangement of the parts embraced in the present and preferred embodiment of my invention in order to impart 15 a definite understanding of the said embodiment. I do not desire, however, to be understood as confining myself to the said specific construction and relative arrangement of 20 parts, as such changes or modifications may be made in practice as fairly fall within the scope of my invention as claimed.

With the lever-plate I arranged as shown it will be observed that when a party approaches the gate and pulls on the adjacent 25 end of the cable R the gate will be caused to swing in a direction away from the party. Now I desire it understood that when preferred the lever-plate I may be arranged on the upright bar H with its straight edge remote from the gate and its curved edge adjacent to the same, when the cable R may be arranged on said lever-plate, so that when 30 a party approaches the gate and pulls on the adjacent end of said cable the gate will be caused to swing open in the direction toward the party. This latter arrangement is 35 advantageous for many reasons, chief among which is that a teamster will naturally open the gate slowly and carefully, for if he did

otherwise the gate swinging toward him in a violent manner would be likely to frighten 40 his horses.

Having described my invention, what I claim, and desire to secure by Letters Patent, is—

1. The combination with a hinge-post having an upright stud on its upper end and also having lateral bearing-wings at an intermediate point of its height; of a gate having an upright at its inner end, a horizontal loop or 50 staple fixed to and extending from said upright and receiving in its bight the stud, and a horizontal plate fixed to the upright and having notches in its edge remote from the upright arranged to engage the bearing-wings. 55

2. The combination with a hinge-post having an upright stud on its upper end provided with a flat arm and also having U-shaped lateral bearing-wings fixed to its face at an intermediate point in its height, and a depression in its face between the said wings; of a gate having an upright at its inner end, a horizontal loop or staple fixed to and extending from said upright and receiving in its bight the stud, a loop or staple fixed to and 60 extending from the upright and disposed at a right angle to the first-mentioned loop or staple, and a flat plate fixed in the second-mentioned loop or staple and having notches in its edge remote from the upright arranged 65 to engage the bearing-wings. 70

In testimony whereof I have hereunto set my hand in presence of two subscribing witnesses.

WILLIAM H. TEABY.
